CLAIM

The ornamental design for eyeglass fittings, as shown and described.

DESCRIPTION

FIG. 1 is a front view of eyeglass fittings, showing my new design;

FIG. 2 is an enlarged view of a portion of FIG. 1;

FIG. 3 is a rear view of the eyeglass fittings of FIG. 1;

FIG. 4 is an enlarged view of a portion of FIG. 3;

FIG. 5 is a perspective view of FIG. 1; and,

FIG. 6 is an enlarged view of a portion of FIG. 5.

The broken lines shown in the drawings are included for the purpose of illustrating environmental subject matter and unclaimed portions of the eyeglass fittings and form no part of the claimed design.
